UNITED STATES PATENT OFFICE.

ROBERT W. SCOTT, OF LEEDS POINT, NEW JERSEY, ASSIGNOR OF ONE-HALF TO LOUIS N. D. WILLIAMS, OF OGONTZ, PENNSYLVANIA.

RIB-KNITTING MACHINE.

No. 901,840.

Specification of Letters Patent.

Patented Oct. 20, 1908.

Application filed August 17, 1906. Serial No. 331,015.

To all whom it may concern:

Be it known that I, ROBERT W. SCOTT, a citizen of the United States, residing in Leeds Point, Atlantic county, New Jersey, 5 have invented certain Improvements in Rib-Knitting Machines, of which the following is a specification.

The object of my invention is to so construct a machine for knitting ribbed fabric, 10 that a fleecing yarn can be interlaced with said fabric in a simple and expeditious manner.

In the accompanying drawings:—Figure 1 is a view partly in side elevation and partly 15 in section, of a rib knitting machine constructed in accordance with my present invention; Fig. 2 is a sectional plan view of the machine on the line *a—a*, Fig. 1; Fig. 3 is a plan or top view of a portion of the machine; 20 Fig. 4 is a view showing one-half of the cylinder cam box of the machine developed on a flat plane; Fig. 5 is a similar view of the other half of the cylinder cam box; Fig. 6 is a plan view of the yarn guides of the 25 machine, and of the cams of the dial cam plate; Fig. 7 is a plan view, partly in section, of the fleecing yarn guide of the machine; Fig. 8 is a sectional view illustrating a modification 30 of the invention; Fig. 9 is a sectional view illustrating the application of my invention to another type of machine; Figs. 10 to 14, inclusive, are views illustrating the operation 35 of the machine, and Fig. 15 is an exaggerated view of a piece of fabric produced upon the machine.

So far as concerns the general construction of the rib knitting machine shown in Figs. 1 to 6, my invention involves no material departure from ordinary practice, except in the 40 means employed for maintaining the needle dial in stationary position, and for imparting rotating movement to the dial cam plate, the invention comprising mainly the combination with a rib knitting machine of a fleecing 45 yarn guide, and a stitch deflector as herein-after described.

In Fig. 1 of the drawings, 1 represents part of the fixed table or bed of the machine which constitutes a bearing for a rotating 50 gear wheel 2, the latter carrying the cylinder cam-box 3, and having also mounted upon it by means of posts 4 the arch 5, as is usual in machines of this type. Secured to the fixed bed plate is the needle cylinder 6, which has

vertical grooves for the guidance of the cylinder needles 7, the latter being actuated by means of cams 9 to 21 inclusive, shown in Figs. 4 and 5, and operating in the manner hereinafter set forth.

Mounted in the hub of the arch 5 is a tubular vertical spindle 22, to the lower end of which is secured, by means of a set screw 23, the needle carrying dial 24, the upper face of the latter being grooved, as shown, for the reception of the radially reciprocating dial 65 needles 25, which are caused to reciprocate by means of cams 26 to 31 inclusive, shown in Fig. 6, these cams being carried by the underside of a dial cam plate 32, which is free to rotate around the spindle 22, and is 70 provided with a projecting arm 33, having at its outer end an adjusting screw 34, which bears against one of the posts 4 of the arch, so that, as the latter rotates with the drive wheel 2, corresponding rotation will be imparted to the dial cam-plate 32. Adjustment of the dial cam-plate and its cams around the axis of the spindle 22 is permitted or effected by turning the screw 34 in one direction or the other, the hub of the arm 33 75 being split and provided with a clamping bolt 35, whereby it is secured to the hub of the cam-plate as shown in Figs. 1 and 2, rise of the dial cam-plate on the spindle 22 being prevented by means of a collar 36, located 80 above the hub of the arm 33, and secured to the spindle by means of a set screw 37.

Owing to the use of the rotating internal yarn guide and stitch deflector, hereinafter referred to, I cannot lock the needle dial 24 90 to the needle cylinder 5, by means of engaging lugs on the inner side of the cylinder and underside of the dial, as usual, hence I am compelled to resort to other means for preventing rotation of the dial. Various means 95 for accomplishing this result may be employed, but in the present instance I have provided annular racks on the needle cylinder and on the spindle 22, these racks engaging with spur wheels carried by a shaft 100 which is mounted in a bearing secured to, and rotating with, the arch structure of the machine.

The annular rack on the needle cylinder is represented at 40, and the annular rack 105 carried by the spindle 22 is represented at 41, a spur wheel 42, at the lower end of a vertical shaft 43 engaging with the rack 40, and a

similar spur wheel 44, at the upper end of said shaft 43 engaging with the rack 41. The shaft 43 is carried by a bearing 45 on a bracket 46, which is secured to one of the 5 posts 4, as shown in Figs. 1, 2 and 3, hence, as said bracket is carried around by the rotating arch structure, the pinions 42 and 44 are caused to rotate uniformly, and there can be no movement of the rack 41 independently of the rack 40 on the needle cylinder, and as the latter is stationary it follows that the rack 41 and the dial 24, controlled thereby, must also remain stationary.

Passing through the tubular spindle 22 is a 15 tubular yarn guide 47, provided at its upper end with a projecting arm 48, which has a split hub 49, with suitable clamp screw and nut whereby it is secured to the yarn guide, this hub resting upon the upper end of the 20 spindle 22 and thus serving for the proper support of the yarn guide in respect to said spindle.

Secured to the projecting lower end of the 25 yarn guide 47 is a bent arm 50, whose outer end constitutes a combined yarn guide and stitch deflector, said outer end having a cam surface 51 (Fig. 7), and at the rear of the same a projecting finger 52, the outer face of which is grooved, as at 53, to form a yarn 30 guiding channel which communicates at its forward end with a yarn passage 54, extending through the guide, said yarn passage being in line with a notch 55 in the vertical portion of the arm 50, so that a yarn passing 35 through the tubular yarn guide 47 can be threaded through the notch 55, passage 54, and grooved channel 53, so as to be delivered from the end of the projecting finger 52 of the guide.

40 The yarn guide 50 operates on the inside of the knitted tube depending from the cylinder and dial needles of the machine, and the cam-face 51 of said guide is located close to the underside of the dial 24, and projects 45 so far beyond the periphery of said dial, and so far also beyond the cylinder needles 7, that, if said guide is caused to rotate with the dial cam-plate, it will deflect the stitches carried by the dial needles to such an extent 50 that the yarn fed by it can be delivered behind said stitches and in front of the cylinder needles 7, (see Fig. 10), the latter rising behind the projecting finger 52 of the guide, so 55 that said yarn can be properly laid in their hooks. (See Fig. 11).

Rotative movement of the tubular yarn guide 47 in consonance with the dial cam-plate 32 and cylinder 3 is effected by contact of a screw 56 at the outer end of the arm 48 60 with a post 57, which is secured to and projects upwardly from one of the posts 4 of the machine, or from some other portion of the rotating arch structure, adjustment of said screw 56 providing for back and forth ad-

justment of the guide 50, so that it may bear 65 the proper relation to the cams of the cam-box and dial cam-plate.

The machine which I have shown in the drawing is what is termed a "two-feed" machine, that is to say, the cylinder cam-box 70 and dial cam-plate have two sets of knitting cams which coöperate with two knitting yarn guides, so as to form two courses of stitches on each rotation of the machine, although it should be understood that my invention is equally applicable to a single feed machine, or to a machine having more than two feeds, with their accompanying sets of cams.

In Fig. 6, the two yarn guides are represented respectively at 60 and 61, said yarn guides being suitably mounted upon the dial cam-plate and rotating therewith in the direction of the arrow, Fig. 6, the knitting yarn being fed through an eye 62, in each yarn 80 guide. At 26, 27 and 28, are represented respectively, the projecting cam, the guard cam, and the retracting cam of the dial cam-plate which operate in conjunction with the knitting yarn guide 60, and at 29, 30 and 31, 85 are represented respectively the projecting cam, the guard cam, and the retracting cam of the dial cam-plate which coöperate with the knitting yarn guide 61. The projecting cam structure, however, is formed so as to 90 present a cam 63 considerably in advance of the cam 26, so as to provide for a projection of the dial needles so far in advance of the knitting point as to provide for the proper action of the yarn guide and stitch deflector 95 50, whereby the stitches are pushed outward upon the dial needles in order to permit of the laying of the fleecing yarn behind them by said guide. This cam 63, however, is not 100 essential, as the guide 50 may, if desired, push out the dial needles as well as the stitches. One-half of the cylinder cam-box has the usual knitting cams, comprising a 105 projecting cam 14, and an adjustable depressor cam 15, for operating the cylinder 110 needles to receive the knitting yarn from the guide 60, and the other half of the cylinder has knitting cams comprising a lift cam 20, and an adjustable depressor cam 21, for operating the needles to receive yarn from the 115 knitting yarn guide 61, a lift and rest cam 16 and a guard cam 17 following the cams 14 and 15, and a lift and rest cam 18 and a guard cam 19 following the cams 20 and 21. In addition to these two sets of knitting cams 120 there are, in the cylinder cam-box, a leveling cam 9 and a set of cams 10 and 11, the cam 10 being a lift cam and the cam 11 a depressor cam. The lateral relation of the yarn guides 54 125 and 62 to the cams of the cam cylinder is shown by dotted lines in Fig. 4, although this does not properly show their vertical re-

lation, as, in the machine, the said guides are further above the cams. The relation of the guides 54 and 62 to the dial cams is shown in Fig. 6.

5 The internal yarn guide 50 of the machine is intended for the control of the fleecing yarn x which is fed through the tubular yarn guide 47, and the cam 10 of the cylinder cam-box raises the cylinder needles behind and close 10 to the end of the finger 52 of said internal yarn guide 50, so as to permit of the placing of the fleecing yarn in the hooks of said needles, as shown in Fig. 11, after it has been placed behind the dial needle stitches which 15 have been projected by the action of the cam-face 51 of said guide, as in Fig. 10. The draft upon the fabric prevents the cylinder wale stitches preceding those in the hooks of the cylinder needles from being pulled over 20 said hooks when the dial stitches are projected as in Fig. 11.

The lift of the cam 10 is not sufficient to cause the cylinder needles to slip their stitches back of the latches, and after the fleecing 25 yarn has been laid in the hooks of these needles the latter are depressed by the action of the cam 11, so as to draw slack loops of fleecing yarn of the required length to give the desired looped face on the knit fabric for 30 fleecing purposes. (See Fig. 12.) The cylinder needles are then raised to the clearing point by the cam 14, that is to say, they rise to such a point that both the knitting stitches and the loops of fleecing yarn will be slipped 35 back of the latches of the needles, as shown in Fig. 13, and, when the needles are depressed by the cam 15, the loops of fabric yarn and the loops of fleecing yarn will be cast together from said needles, over the new 40 loops of knitting yarn. (See Fig. 14). As a result the fleecing yarn will be interlaced with the fabric without being knit into it, that is to say the loops of fleecing yarn will not be drawn through loops of fabric yarn. 45 (See Fig. 15.)

As shown, I have provided for the introduction of the fleecing yarn in alternate courses only of the knitted web, but it will be evident that the same may be used in connection 50 with each course, if desired, by providing a proper equipment of cams 10 and 11 in advance of the knitting cams 20 and 21, and by duplicating the guide 50, and it will also be evident that by separating the cylinder needles, either in the plane of their reciprocation 55 or in a plane transverse thereto the fleecing yarn can be fed in front of some of said needles and behind the others, so that it will not be interlaced with every cylinder needle wale 60 of the fabric. Although convenient it is not necessary that the stitch deflector and fleecing yarn guide shall form part of the same element of the machine, and if desired, the fleecing yarn guide and stitch deflector may be

arranged adjacent to the inner side of the 65 needle cylinder 6 instead of to the underside of the needle dial, there being a corresponding transposition in the movements of the cylinder and dial needles, so that the fleecing 70 yarn will be laid underneath the cylinder 75 needle stitches and on top of the dial needles as shown in Fig. 8. In this case, the central tubular yarn guide 47 will not be necessary, since, although the fleecing yarn guide is inside of the cylinder of the machine, and inside of the needle angle, it is not inside of the tubular web depending from the needles.

I have shown my invention as embodied in a machine in which the needle cylinder and dial are stationary and the cylinder cam box 80 and dial cam plate rotate, but my invention is of course equally applicable to a machine in which the reverse is true.

It is not always necessary in carrying out my invention, to employ an internal fleecing 85 yarn guide and stitch deflector, for instance I may, as shown in Fig. 9, employ an external fleecing yarn guide 50^a of a character similar to that shown and described in my Letters Patent #577,789, dated February 23, 1897, 90 this yarn guide acting upon the butts of the dial needles 25 and serving to project them into an annular needle dial 24^a, located outside of the main needle dial 24 and suitably mounted upon the needle cylinder 6. The 95 fleecing yarn guide 50^a will, however, be modified, as compared with that of the machine of the previous patent, so as to project the dial needles to a greater extent than before in order to permit said fleecing yarn 100 guide to lay its yarn in the hooks of the cylinder needles, and the cylinder cam-box will be provided with cams 9, 10 and 11, as described, for operating the cylinder needles to receive and draw loops of the fleecing yarn. 105

I claim:—

1. The combination of two sets of needles, knitting cams, and knitting yarn guide or guides of a rib knitting machine, with means for projecting the stitches carried by one set 110 of needles and means for feeding a fleecing yarn behind said stitches and into engagement with the other set of needles.

2. The combination of the two sets of needles, knitting cams, and knitting yarn guide 115 or guides of a rib knitting machine, with means acting directly upon the stitches carried by one set of needles to displace them from their normal position and means for laying a fleecing yarn behind said stitches 120 and into engagement with the other set of needles.

3. The combination of the two sets of needles, knitting cams, and knitting yarn guide or guides of a rib knitting machine, with a 125 fleecing yarn guide and a stitch deflector operating on the inside of the machine.

4. The combination of the two sets of nee-

- dles, knitting cams, and knitting yarn guide or guides of a rib knitting machine, with a fleecing yarn guide and a stitch deflector operating on the inside of the machine, and 5 a tubular guide for conveying the fleecing yarn from the outside to the inside of the machine.
5. The combination of the two sets of needles, knitting cams, and knitting yarn guide or guides of a rib knitting machine, with an 10 internal fleecing yarn guide having a deflecting surface for acting upon the stitches upon one set of needles, and a finger for feeding the fleecing yarn to the other set of needles.
- 15 6. The combination of the needle cylinder and dial, and their needles, the cylinder cam-box and dial cam-plate and their cams, the knitting yarn guide or guides, and an internal fleecing yarn guide and stitch deflector, 20 operating to deflect the stitches on the dial needles and lay the fleecing yarn behind the same and feed it to the cylinder needles.
7. The combination of a fixed needle cylinder, a needle dial, a rotating cylinder cam 25 box, a dial cam plate, a knitting yarn guide or guides, an internal fleecing yarn guide and stitch deflector, means for preventing ro-

tation of the needle dial, and means for causing the dial cam plate to rotate with the cylinder cam box.

8. The combination of the two sets of needles, knitting cams, and knitting yarn guide or guides of a rib knitting machine, with means for projecting the stitches carried by one set of needles, means for feeding a fleecing yarn behind said stitches and into engagement with the other set of needles, and means for looping said fleecing yarn.

9. The combination of the two sets of needles, knitting cams, and knitting yarn guide or guides of a rib knitting machine, with means for projecting the stitches carried by one set of needles, means for feeding a fleecing yarn behind said stitches and into engagement with the other set of needles, and 40 means to actuate the latter needles to loop the fleecing yarn.

In testimony whereof, I have signed my name to this specification, in the presence of two subscribing witnesses.

ROBERT W. SCOTT.
